UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed March 8, 1923. Serial No. 626,616.

This invention relates to typewriting machines, especially those used for bookkeeping. It is sometimes desired to type the same matter on a ledger-sheet form, a longitudinally-folded pack of work-sheets bearing a printed statement-form and a pack of proof-sheet forms, all of which forms have a number of similar columns to receive similar entries. As these forms are usually printed on different-sized sheets of paper, and have other columns to receive other typed matter, in addition to those similar columns referred to, it is difficult to bring the similar columns into registration. Moreover, all of the matter is not to be typed during one typing operation, and the different sheets and packs must be removed from and reinserted into the machine possibly a dozen or more times during the course of a month.

Sheet-collating means, to simplify these constantly repeated operations of aligning and typing, constitutes one of the features of this invention.

Another feature of this invention is the provision of a carbon-pack bearing identification means and having carbon-sheets that may be interleaved between the folds of a longitudinally-folded pack of work-sheets bearing printed statement-forms, so that the latter may be filed away between the times when entries are being typed upon it.

Still another feature of this invention is the provision of a carbon-pack having carbon-sheets of different widths so that, when work-sheets are assembled therein, parts of those work-sheets will be left exposed to receive type-impressions instead of carbon-impressions of typed matter.

Other features and advantages will hereinafter appear.

In the accompanying drawings,

Figure 1 is a front view of the platen and carriage of a bookkeeping machine, showing the sheet-collating means mounted thereon, the relative positions of a ledger-sheet, a longitudinally-folded statement-pack and a proof-sheet pack being indicated thereon by dot-and-dash lines.

Figure 2 is a top view of the sheet-collating means with the positions of the different sheets and packs shown in dot-and-dash lines.

Figure 3 is a sectional view through the platen and carriage of a bookkeeping machine, showing the sheet-collating means

mounted thereon, the relative position of the various sheets and packs being shown in dot-and-dash lines with the exception of the proof-sheet, which is shown in full lines.

Figure 4 is a detail perspective view of a paper-clamp which is part of the sheet-collating means.

Figure 5 is a detail perspective view of a table-section which is part of the sheet-collating means.

Figure 6 is a perspective view of a carbon-pack having carbon-sheets of different widths, showing several proof-sheets assembled therein.

Figure 7 is a perspective view of a smaller carbon-pack fitted with a blank shield, at its top edge, on which matter may be typed.

Figure 8 is a perspective view of a longitudinally-folded pack of work-sheets on which may be printed a statement-form.

Figure 9 is a perspective view of the same longitudinally-folded pack shown in Figure 8, with its work-sheets interleaved with the carbon-sheets of the carbon-pack shown in Figure 7.

As is usual in bookkeeping machines, a platen 10 is mounted on a platen-axle 11 which is supported by a carriage 12. The usual feed-rolls 13 and 14 are used to cooperate with a rear paper-table 15 in guiding work underneath and around the platen 10. Paper-fingers 15^a, mounted to be adjustable longitudinally of the platen 10, are provided to secure a work-sheet or pack in position while other work-sheets or packs are being inserted in the machine, and a writing-line scale 15^b is provided to assist in bringing those work-sheets or packs into longitudinal registration.

Mounted on the ends and running longitudinally of the carriage 12 is a table-supporting bar 16, which has adjustably mounted thereon the three collating table-sections 17, 18 and 19. The left edge of the table-section 17 is upturned ninety degrees to form a side guide 20, which has fastened to it near its lower end a paper-clamp 21. The body 22 of the paper-clamp 21 has depending ears 23 into which is journaled a shaft 24. Mounted near the ends of the shaft 24, where it passes through the ears 23, are the clamping arms 25 and 26, which are provided with a pair of paper-gripping pads 27 which press the work-sheets against the table-section 17 and also prevent said sheets

from skewing while being typed upon. The clamping arm 25 is further provided with a finger-piece 28, which may be used to move the clamping arms 25 and 26 to or from the clamping position. The clamping arm 26 is further provided with an ear 29, in which is stop 33 is provided on one of the ears 23 to the clamp 21 has a similar pin 31 fastened therein, and a spring 32 fastened to the two pins 30 and 31 is so positioned, with relation to the pivotal connection between the clamping arms 25 and 26 and the ears 23, that it will hold the clamping arms 25 and 26 in either operative or inoperative position. A stop 33 is provided on one of the ears 23 to limit the movement of the clamping arms 25 and 26 in inoperative direction. Fastened on the clamping arms 25 and 26 near their points of contact are the two ends of a gage-bar 34.

The right edge of the table-section 18 is upturned ninety degrees to form a side guide 35, which is provided with lugs 36, which are bent over toward the left until parallel with the body of the table-section 18, and thus provide retaining means to confine the edge of a work-sheet or pack within the table-section 18.

The right edge of the table-section 19 is upturned ninety degrees to form a side guide 37.

For the purpose of illustrating the operation, let us consider the account of John Doe with the X Company. Mr. Doe sends in his order for goods, which is given to a stenographer for typing. It is the practice of the X Company to require this order to be entered on a ledger-sheet 38, a longitudinally folded statement-pack 39 containing four plies or work-sheets 39^a and a proof-sheet pack 40 made up of two work-sheets 40^a. The ledger-sheet 38 is devoted exclusively to Mr. Doe's account, and entries are made on it at different times, as orders are received by the company, until the sheet has been filled with such entries. Mr. Doe's name, address, and other matter which might be required on the ledger-sheet exclusively, are typed separately on its heading. Between the times of typing, the ledger-sheet 38 may be filed with other similar ledger-sheets in a loose-leaf binder. The longitudinally-folded statement-pack 39 is also used exclusively for Mr. Doe's account, entries being made on it at different times during the course of a month as orders are received from Mr. Doe, it being filed away with other similar longitudinally-folded statement-packs between the times of typing. At the end of the month one of the work-sheets 39^a of the longitudinally-folded statement-pack 39 is used as a monthly statement to Mr. Doe, and the other work-sheets 39^a are used for interdepartmental business within the X Company.

For the purpose of transferring the matter typed on the ledger-sheet 38 to the various work-sheets 39^a of the longitudinally-folded statement-pack 39, a carbon pack or book 41 made up of the carbon-sheets 41^a 70 stitched together at 42 is interleaved between the work-sheets 39^a, as shown in Figure 9. The carbon-pack 41 is provided with a blank tab or flap 43, which is superimposed over the top carbon-sheet 41^a and is 75 therefore on the outside of the longitudinally-folded statement-pack 39 and the carbon-pack 41 when they are assembled. The tab 43 bears a heading-form similar to the heading of the longitudinally-folded statement-pack 39, and, when in the superimposed position described above, the two headings are in registration. Mr. Doe's name and address are typed separately in the heading on the tab 43, and, of course, this matter is 80 transferred to the headings of all of the work-sheets 39^a at the same time. As was stated above, the longitudinally-folded statement-pack 39 is filed between times of typing, and, as the carbon-pack 41 is allowed to remain assembled with it, it will be readily perceived that the tab 43 provides means for quick identification and eliminates the possibility of using Mr. Doe's statement with some ledger-sheet not his own. 95

It will be further seen, by referring to Figure 7 of the drawings, that the end 44 of the tab 43 is brought around the upper edges of the carbon-sheets 41^a and extends down the back of the last carbon-sheet 41^a 100 a sufficient distance to receive the stitching 42. When the carbon-sheets 41^a are being assembled in the carbon-pack 41, it will be seen that the crease or fold 45 in the tab 43 forms an aligning means for the carbon-sheets 41^a, and also provides a stiff straight leading edge for the carbon-pack 41 when it is to be threaded into the machine. It will also be seen that the stitching 42 provides an aligning edge for the leading edges 110 of the work-sheets 39^a when the longitudinally-folded statement-pack 39 is assembled with the carbon-pack 41. The use of the carbon-pack 41 also eliminates the necessity for interleaving the longitudinally-folded 115 statement-pack 39 with carbon-sheets each time it is to be used, that operation having to be performed only once each month.

By referring to Figure 9 of the drawings, it will be seen that the carbon-sheets 41^a are 120 somewhat narrower than the work-sheets 39^a. In practice this difference in width is made to be from one-eighth to one-quarter of an inch. The purpose of this difference in width will be disclosed hereinafter. 125

Unlike the ledger-sheet 38 and the longitudinally-folded statement-pack 39, which are used only to receive entries taken from Mr. Doe's orders, the proof-sheet pack 40 is retained in the machine from the time 130

that the stenographer starts transcribing matter from the day's orders until it is completely filled, and consequently it receives not only transcriptions from Mr. Doe's orders, similar to those typed on the ledger-sheet 38 and the longitudinally-folded statement-pack 39, but transcriptions from the orders of other customers as well. The proof-sheet pack 40 is made up of a carbon-pack 46 having carbon-sheets 47 and 48 fastened by stitching 49 under a flap 50 formed from the top edge of a comparatively stiff paper-back 51. The carbon-sheets 47 and 48 are aligned by a crease or fold 52 in the paper-back 51, which also forms a stiff straight leading edge similar to the crease or fold 45 of the carbon-pack 41 already described in detail.

By referring to Figure 6 of the drawings, it will be noted that the carbon-sheet 48 is considerably narrower than the carbon-sheet 47, so that a wide margin 40^b is left exposed on the upper work-sheet 40^a of the proof-sheet pack 40. It has not been mentioned that the work-sheets 40^a of the proof-sheet pack 40 are not provided with headings for names and addresses similar to those of the ledger-sheet 38 and the longitudinally-folded statement-pack 39. This omission of a heading from the work-sheets 40^a is made because the work-sheets 40^a receive transcriptions from other orders besides those of Mr. Doe, as has been explained. It is desirable, however, to make identification of all transcriptions made to the work-sheets 40^a as easy as possible, and, to accomplish this, the name of each customer is typed in the exposed marking 40^b of the work-sheet 40^a opposite the last line of matter transcribed from his order.

Having prepared a ledger-sheet 38 and a longitudinally-folded statement-pack 39 assembled with a carbon-pack 41, with the name and address of Mr. Doe, the stenographer inserts a proof-sheet pack 40 into the machine and advances it until its first writing line appears at the writing-line scale 15^b,—which provides a longitudinal registration means, meanwhile guiding its leading edge 52 underneath the bar 16 and in back of the collating-table sections 17, 18 and 19, as shown in Figures 1 and 2 of the drawings. The paper-fingers 15^a provide guiding and holding means for the proof-sheet pack 40 while the statement-pack 39 and the ledger-sheet 38 are being placed in the machine. The longitudinally-folded statement-pack 39 with its assembled carbon-pack 41 is next inserted into the machine and drawn around the platen to a position over the proof-sheet pack 40. The leading edge 45 of the assembled packs 39 and 41 is guided over the collating table formed by the two collating-table sections 17 and 18, and is drawn forward until the

first writing line of the longitudinally-folded statement-pack 39 appears at the writing-line scale 15^b. The right edge of assembled packs 39 and 41 is now held in place on the collating table by the lugs 36 79 on the side guide 35. The right-hand edges of the narrow carbon-sheets 41^a were previously shaken into alignment with the right-hand edges of the slightly wider work-sheets 39^a which left a margin 39^b as 75 shown in Figure 9. This margin 39^b is now engaged by the gripping pads 27 on the paper-clamp 21, which is thrown to operative position to hold the longitudinally-folded statement-pack 39 in place, as shown 80 in Figures 1 and 2 of the drawings.

The ledger-sheet 38 is now inserted and brought around the platen and over the longitudinally-folded statement-pack 39 to a position on a collating table formed by the 85 collating-table sections 17 and 19. As the ledger-sheet 38 is advanced to bring its first writing line to the writing-line scale 15^b, its right-hand edge is guided by the side guide 37 on the table-section 19, and its left-hand edge is guided by the gage-bar 34 on the paper-clamp 21, as shown in Figures 1 and 2 of the drawings.

It will be noted that the righthand portion of the ledger-sheet 38 extends considerably beyond the right-hand edge of the statement-pack 39, and upon this portion of the ledger-sheet are typed items of the account which it is desired to have appear only on the ledger-sheet and proof-pack. 95

The similar columns, which appear on the ledger-sheet 38, the longitudinally-folded statement-pack 39 and the proof-sheet pack 40, are now all in registration as are the first writing lines of those sheets and packs, and, after bringing the feed-rolls 13 and 14 into operative position and releasing the paper-clamp 21, the operator is ready to transcribe matter from Mr. Doe's order. 105

After completing the transcription of Mr. Doe's order, the stenographer places a mark 53 in the margin 39^b opposite the last typed line 54 of the transcribed matter, and then back-spaces the carriage to the right to enable her to write Mr. Doe's name in the exposed margin 40^b of the top proof-sheet 40^a opposite the last line of matter typed in the similar columns. The mark 53 placed in the margin 39^b will disclose the last line of writing on the longitudinally-folded statement-pack 39 without having to raise the top carbon-sheet 41^a when the longitudinally-folded statement-pack 39 is next taken from its file for transcribing additional matter thereon. Mr. Doe's name typed in the margin 40^b 115 of the proof-sheet 40^a not only serves to locate the last line of writing on that sheet, which will necessarily be covered up when different ledger-sheets 38 and longitudinally-folded statement-packs 39 are superimposed 120

thereon, but also provides means for easy identification of the items which appear on those writing lines above the one on which the name is written. The stenographer then 5 removes the ledger-sheet 38 and the longitudinally-folded statement-pack 39, together with the carbon-pack 41 assembled therein, but leaves the proof-sheet pack 40 in the machine to be retained by the paper-fingers 15^a 10 in position to receive matter on its next writing line.

A ledger-sheet 38 and a longitudinally-folded statement-pack 39 bearing the name and address of another customer are now 15 inserted in the machine, in the same manner as were the similar sheet and pack of Mr. Doe, with their first writing lines in registration with the next succeeding writing line from that on which Mr. Doe's name appears 20 on the proof-sheet 40. The entire process may now be repeated.

Variations may be resorted to within the scope of the invention, and portions of the improvements may be used without others.

25 Having thus described my invention, I claim:

1. In a typewriting machine, in combination, a revolute platen, means for guiding and holding a work-sheet or pack in position thereon, gaging means for gaging a second work-sheet or pack to bring it into lateral registration with said first-named work-sheet or pack, said gaging means comprising a movable gage having a body with 30 two upstanding ears formed thereon, a gage-bar fastened to two arm-members movably mounted between said upstanding ears, a finger-piece for actuating said gage-bar, a spring to hold said gage-bar in either operative or inoperative position, and a stop to limit the movement of said gage-bar in inoperative direction.

2. In a typewriting machine, in combination, a revolute platen, means for guiding and holding a work-sheet or pack in position thereon, means for supporting a second work-sheet or pack in position on top of said first-named work-sheet or pack, said supporting means including a collating-table section having a body-portion pierced with a slot to permit transverse adjustment of said table-section, an upturned guide-portion having its forward or lower edge inclined to assist the passage of work-sheets 45 or packs thereover, and duplicate ear or lug portions formed on said up-turned guide-portion and bent to a position parallel with said body-portion to form means for retaining a work-sheet or pack in close proximity to said body-portion and in a flattened position thereon.

3. In a typewriting machine, in combination, a revolute platen, means for guiding and holding a work-sheet or pack, in position thereon, a collating device adjacent

the front of the platen, comprising a left table, a right table and an intermediate table, means for guiding and securing the left margin of a second work-sheet or pack upon said left table, means for guiding and holding the right edge thereof upon the intermediate table so that said second work-sheet or pack lies over said first-mentioned work-sheet or pack, and means associated with said left table and said right table for guiding a third work-sheet to position in superposed relation to said first and said second mentioned work-sheets or packs.

4. In a typewriting machine, in combination, a revolute platen, means for guiding and holding a work-sheet or pack in position thereon, a collating device adjacent the front of the platen including a guide for the left edge of a second work-sheet or pack, a clamping device for holding said second work-sheet or pack in adjusted position with relation to said first-mentioned work-sheet or pack, means for guiding and holding the right edge of said second work-sheet or pack, and means for guiding a third work-sheet to position, so that the left portion thereof lies over said second work-sheet or pack while the right portion extends beyond the right edge of said last-named work-sheet or pack and overlies the right-hand portion 95 of said first-named work-sheet or pack.

5. In a typewriting machine, in combination, a revolute platen, means for guiding and holding a work-sheet or pack in position thereon, a collating device adjacent the front of the platen including a guide and a clamp for guiding and holding the left edge of a second work-sheet or pack in adjusted position with relation to said first-mentioned work-sheet or pack, a guide adjacent the intermediate portion of said collating device and including retaining fingers for the right edge of said second work-sheet or pack, guide means carried by said clamp, and guide means carried upon the right-hand portion of said collating device, both of said last-mentioned guide means co-operating in guiding a third work-sheet to position in superposed relation to said second work-sheet or pack.

6. In a typewriting machine, in combination, a revolute platen, means for guiding and holding a work-sheet or pack in position thereon, a collating device including a bar extending parallel with the platen, a left table, a right table, and an intermediate table, each adjustably secured upon said bar and disposed adjacent the upper portion of the front of said platen, a guide and a clamp associated with said left table for guiding and holding the left portion of a second work-sheet or pack in adjusted position, a guide and retaining fingers carried by said intermediate table for holding the right-hand portion of said second work-

sheet or pack, a guide-piece fixed to said clamp for determining the position of the left edge of a third work-sheet, and a guide carried by said right table for determining 5 the position of the right edge of said third work-sheet.

7. In a typewriting machine, in combination, a carriage, a revoluble platen, means for guiding and holding a work-sheet or 10 pack in position thereon, a collating device including a bar bridging said platen and extending in parallelism therewith, the ends of said bar being fixed to the carriage, a left table, a right table, and an intermediate 15 table adjustably secured upon said bar and disposed adjacent the upper portion of the front of said platen, a guide carried by the outer edge of said left table for guiding the left edge of a second work-sheet or pack, 20 a clamp pivoted upon said left table and including a paper-gripping member fitted with pads for clamping the left margin of said second work-sheet or pack against said left table, a guide carried by said intermediate 25 table for the right edge of said second work-sheet or pack and including retaining fingers therefor, a guide carried upon the free end of said clamp for guiding the left edge of a third work-sheet, and a guide carried 30 by the outer edge of said right table for guiding the right edge of said last-named sheet.

8. In a typewriting machine, in combination, a revoluble platen, means for guiding 35 and holding a wide work-sheet or pack in position thereon, means for holding a narrow work-sheet or pack in superposed relation to said first-named work-sheet or pack and substantially intermediate the side edges 40 thereof, so as to provide an uncovered portion adjacent the left of said wide work-sheet and an uncovered portion adjacent the right thereof, and means for guiding another work-sheet to position, so that the left 45 portion thereof covers the major portion of the width of said narrow work-sheet while the right portion extends beyond the right edge of said narrow work-sheet and over the uncovered portion adjacent the right of said 50 wide work-sheet.

9. In a typewriting machine, the combination of a revoluble platen, a front table for supporting a work-sheet extending around said platen, and a paper-clamp including a pair of arms pivoted on said front table, a pad on each of said arms for pressing said sheet against said table, said pads being spaced apart to prevent skewing of said sheet, releasable resilient means for 55 forcing said arms in a direction to press said pads against said work-sheet, and a side gage extending between and rigid with said arms for side-edge guiding a second work-sheet on said front table, superimposed over the first-mentioned work-sheet.

10. In a typewriting machine, the combination of a revoluble platen, and a collating device for work-sheets or packs extending around said platen, including a left front table and a right front table co-operating to 70 support an outer work-sheet and an intermediate front table co-operating with said left table to support a narrower inner work-sheet or pack, said intermediate table having its upper edge spaced below the upper 75 edges of said left and right front tables to provide room for the manual gripping of said work-sheets or packs.

11. In a typewriting machine, the combination of a revoluble platen, and a collating 80 device for work-sheets or packs extending around said platen, including a left front table and a right front table co-operating to support an outer work-sheet and an intermediate front table co-operating with said 85 left table to support a narrower inner work-sheet or pack, said intermediate table having its upper edge spaced below the upper 90 edges of said left and right front tables to provide room for the manual gripping of said work-sheets or packs, said left and intermediate front tables having left and right side-edge guides, respectively, for said inner work-sheet or pack and said right table having a right side-edge guide for said 95 outer work-sheet.

12. In a typewriting machine, the combination of a revoluble platen, and a collating device for work-sheets or packs extending around said platen, including a left 100 table having a forwardly-directed flange, an intermediate table having a second forwardly-directed flange, said flanges co-operating to guide an inner work-sheet or pack, a right table having a forwardly-directed 105 flange, and a gage on said left table co-operating with the last-mentioned flange to guide an outer work-sheet, said last-mentioned flange being of greater depth than the second flange to effectually maintain engagement with said outer sheet.

13. In a typewriting machine, the combination of a revoluble platen, and a collating device for work-sheets or packs extending around said platen, including a left 115 table having a forwardly-directed flange, an intermediate table having a second forwardly-directed flange, said flanges co-operating to guide an inner work-sheet or pack, a right table having a forwardly-directed 120 flange, and a gage on said left table co-operating with the last-mentioned flange to guide an outer work-sheet, said last-mentioned flange being of greater depth than the second flange to effectually maintain engagement with said outer sheet, said second flange having a laterally-directed portion to prevent the escape of said inner work-sheet or pack.

JESSE A. B. SMITH.
